FUEL INJECTOR PUMP FOR INTERNAL-
COMBUSTION ENGINESHarry da Costa, London, England, assignor to The
Plessey Company Limited, Ilford, Essex, Eng-
land, a British companyApplication April 18, 1942, Serial No. 439,516
In Great Britain April 18, 1941

3 Claims. (Cl. 103—38)

This invention relates to liquid injection pumps and is particularly applicable to fuel injection pumps for injecting accurate quantities of liquid fuel into the engine or to that part of the engine to which fuel is normally to be supplied. In injection pumps of the more usual kind the quantity of fuel pumped at each stroke depends upon the co-operation between the pump plunger and a port or ports in the cylinder in which the plunger is reciprocated. In consequence very precise setting of the pump plunger in the cylinder is necessary and, furthermore, the edge of the port which provides the requisite cut-off in conjunction with the plunger must be accurately maintained. An object of the present invention is to provide a pump in which the disadvantages of accurate relationship between the plunger and the port opening is avoided, and the invention is applied to that type of injection pump in which the pump plunger is so formed as to comprise within it a liquid receiving chamber by means of which liquid received within it is discharged through the pump outlet.

According to the present invention a piston and cylinder liquid injection pump comprises in combination a pump cylinder, inlet and outlet ports opening into said cylinder at positions spaced axially apart in the wall thereof, a reciprocating pump plunger having in it a fuel chamber which, during a stroke of the plunger, is moved from a position in which it communicates with the inlet port to a position in which it communicates with the outlet port, and means associated with said chamber for expelling part at least of the charge contained therein through the outlet port.

More particularly, a pump according to the invention comprises in combination a pump cylinder, inlet and outlet ports opening into said cylinder at positions spaced axially apart in the wall thereof, a reciprocating pump plunger formed in two co-operating and axially aligned portions which provide between them a collapsible liquid receiving chamber, said chamber being moved during a stroke of the plunger from a position in which it communicates with the inlet port to a position in which it communicates with the outlet port, and means to cause relative approach of the two plunger portions in order to expel part at least of the charge contained in the said chamber.

The pump is preferably operated to reciprocate one of the parts of the plunger with a constant stroke, and a further feature of the invention consists in the provision for adjustment of the

means limiting the movement of the other part of the plunger in order to vary the quantity of fuel delivered at each stroke of the pump.

In order that the invention may be more clearly understood, one preferred example will now be described with the aid of the accompanying drawings, in which—

Figures 1 and 2 illustrate one form of the invention in two sectional views in planes at right angles to one another respectively, each section being in a plane containing the axis of the pump plunger;

Figure 3 is a fragmentary view similar to Figure 1 of a modified form of the invention; and

Figure 4 is another sectional view similar to Figure 1, showing a still further modification of the invention.

The pump body 10 has a cylindrical bore 11 of uniform diameter forming the pump cylinder in which the pump plunger 12, 13 is slidable. The part 12 of the plunger projects from one end of the cylinder and engages with a rotary cam 14 for reciprocating the plunger against the action of a return spring 15. The cam 14 is secured to

25 a spindle 16 by which it is rotated.

The pump body has an inlet port 17 and an outlet port 18 opening into the pump cylinder and these ports are spaced apart, lengthwise of the cylinder, by a distance approximately equal

30 to the stroke of the pump plunger.

The pump plunger is formed in two parts 12 and 13 previously referred to arranged end to end in axial alignment. The main part 12 which is actuated by means of the cam 14 is formed with

35 a bore 19 in its upper end and receives in it the extreme end of a reduced portion or stem 20 of the other part 13 of the plunger. Stem 20 carries a transverse anchor pin 21 engaging at its ends lengthwise in slots 22 in the main part 12 of the plunger thereby enabling the part 13 to move relatively to part 12 to a limited extent. A coiled compression spring 23 is provided surrounding the stem 20 and acts at its ends on the upper end of the main part 12 and on a

40 shoulder 24 of the part 13 so as normally to hold the two parts of the plunger separated to a maximum extent. The annular space formed in the plunger by provision of and surrounding stem 20 constitutes the fuel chamber aforesaid, and in

45 one extreme position of reciprocation of the plunger this chamber is opposite the inlet port 17 and at the other extreme position is opposite the delivery port 18. In the upper end of the cylinder, that is to say, that end adjacent the

50 auxiliary part 13 of the plunger, there is screw-

55

threaded a stop 25 for adjustably limiting the movement or stroke of the auxiliary part 13 of the plunger.

In operation, fuel supplied to the inlet port 17 charges the fuel chamber formed in the plunger around stem 20 at one end of the plunger stroke and the fuel in this chamber is carried along the cylinder by means of the plunger towards the delivery port. When this charge of fuel is being carried between the inlet and delivery ports it is trapped in the fuel chamber and sealed therein by the two parts of the plunger in co-operation with the wall of the cylinder. When this chamber has reached the delivery port movement of the auxiliary part 13 of the plunger is limited by the stop 25 while the main part of the plunger continues its full movement to the end of the stroke. Thus, the two parts of the plunger are relatively moved against the action of spring 23 to reduce the volume of the fuel chamber and to deliver a portion of the fuel content in the plunger fuel chamber to the delivery port 18 past a non-return valve 26 provided therein. The quantity of fuel ejected from the pump by the above-described relative movement of the two parts of the plunger is accurately controlled by the position of the stop 25 and in consequence accurate delivery of fuel through the delivery port 18 is obtained on each stroke of the plunger.

Stop 25 instead of being screwthreaded into the pump cylinder may consist of a cam 125 as illustrated in Figure 3 or any other preferred means which serves adjustably to limit movement of the auxiliary part 13 of the plunger may be employed. In the case of a multiple pump unit for multi-cylinder engines, screwthreaded members such as 25, cams such as 125 or the like may be suitably interconnected for simultaneous control.

A vent 27 is provided for the cylinder beyond the outer end of the auxiliary part 13 of the plunger so as to prevent any fluid pressures being developed which would act upon this part of the plunger to tend to retard its movement.

Inlet ports 17 may be arranged to communicate by way of the fuel chamber formed in the plunger with another port 28 displaced around the cylinder from the inlet port so that fuel may pass through the pump body by way of the fuel chamber when the latter is in the appropriate position in order to feed a plurality of pumps mounted side by side. Alternatively, this additional port 28 may be employed as a vent or bleed in the case in which fuel is gravity fed to the inlet port.

In another alternative form, for instance, where viscous fuels are used, the fuel may be applied to the inlet port 17 under pressure by means of a pump and the additional port 28 may be utilised to provide a return for fuel to the pump so as to have a constant circulation of fuel in order to prevent air-locks from occurring.

In the foregoing examples of the invention, after delivery of the fuel and on the return stroke of the combined plunger 12, 13, the fuel space expands and, particularly in the case of light fuels, may be found to give rise to trouble due to vaporisation of part of the fuel remaining in the fuel chamber. In order to avoid this difficulty a construction similar to that illustrated in Figure 4 is found to be preferable. In this case, the pump casing including the pump body 10, and the two-part pump plunger 12, 13 is provided as before together with an actuating cam 14 and an adjustable stop 25. In this case, however, a fuel inlet 117 and a fuel outlet 118 are arranged in line with one another and are controlled by non-

return valves 119 and 120 respectively. A light spring 23 may be provided as before to tend always to maintain the two parts of the plunger separated to a maximum extent or, if desired, this spring may be omitted and the fuel feed pressure through the inlet 117 may be relied upon to separate the two plunger parts immediately after a fuel injection operation has taken place.

With the construction just described in connection with Figure 4, the cam 14 only reciprocates plunger 12, 13 through a very short stroke so that the fuel chamber surrounding stem 20 is never removed from its position of communication with the inlet 117. In operation, as plunger 12 is lifted by cam 14 part 13 travels with part 12 until stop 25 is reached, whereafter the final movement of part 12 under the action of cam 14 ejects fuel past non-return valve 120 through delivery conduit 118 to the engine and on the return stroke, immediately the parts 12 and 13 commence to separate further fuel is fed into the enlarging fuel chamber through conduit 117 past non-return valve 119. Thus, the fuel chamber is always maintained full with fuel and no occasion arises to cause any material vaporisation of the fuel as the pressure in the fuel chamber is reduced.

It will be appreciated that the pump according to this invention does not rely on the cut-off provided by the plunger in co-operation with an edge of a port or ports in the cylinder in order to determine the amount of fuel delivered on each stroke of the plunger. It is a further advantage of a pump according to this invention that alteration by adjustment of stop 25 in the quantity of fuel delivered on each stroke does not vary the finishing time of the delivery, and any alteration in the quantity of fuel delivered is obtained by changing the position in the stroke of the plunger at which delivery commences.

I claim:

1. A piston-and-cylinder fuel-injection pump for internal-combustion engines comprising in combination a pump plunger formed in two relatively axially movable parts providing between them a fuel chamber, a pump cylinder in which the two-part plunger is received and which has inlet and delivery ports communicating with the fuel chamber in the pump plunger, a spring housed within the cylinder and interposed between adjacent extremities of the two parts of the pump plunger and normally tending to separate them to enlarge the fuel chamber to its full extent, and plunger actuating means serving to reciprocate the plunger and periodically to reduce the capacity of the chamber by effecting relative movement between the two parts.

2. A piston-and-cylinder fuel-injection pump for internal-combustion engines comprising in combination a pump plunger formed in two relatively axially movable parts providing between them a fuel chamber, means interconnecting the two movable plunger parts to permit axial movement between them to a predetermined limited extent, a pump cylinder in which the two-part plunger is received and which has inlet and delivery ports communicating with the fuel chamber in the pump plunger, a spring housed within the cylinder and interposed between adjacent extremities of the two parts of the pump plunger and normally tending to separate them to enlarge the fuel chamber to its full extent, and plunger actuating means serving to reciprocate the plunger and periodically to reduce the capacity of the chamber by effecting relative movement between the two parts.

3. A piston-and-cylinder fuel-injection pump for internal-combustion engines comprising in combination a pump barrel, a pump plunger formed in two parts sliding end to end within the barrel, means interconnecting the two plunger parts to permit axial movement between them to a predetermined limited extent, inlet and outlet delivery ports opening into the pump cylinder in the region of the pump chamber formed at the junction of the pump plungers, a spring housed within the cylinder and interposed between adja-

cent extremities of the pump plungers tending always to separate those ends, a spring operating on one of the plunger parts tending to withdraw it and its companion part from the cylinder, an eccentric operating on the end of the plunger in opposition to the external spring and an adjustable stop limiting movement of the other plunger part in opposition to the movement imparted by the eccentric, all for the purpose described.

10

HARRY DA COSTA.
